LIGHTING UNIT

Application filed June 16, 1928. Serial No. 285,853.

This invention relates to light distributing units and more particularly to lighting units especially adapted for the purposes of highway and flood lighting.

5 It is among the primary objects of this invention to provide an exterior lighting device which serves not only to illuminate the highway but also to flood-light adjacent buildings, the device being constructed in the form of a 10 compact unit embodying two sources of light, one for the purpose of highway illumination and the other for the purpose of flood-lighting.

A further object of the invention is the provision of a combined highway and flood-lighting unit embodying two separate and distinct sources of light, that source which is utilized for highway lighting purposes being fixed in position while that which is designed for 20 flood-lighting purposes is mounted independently of the former and in such manner as to afford a wide range of movement through which the rays of light emanating from said flood-lighting source may be directed.

25 A still further object of the invention is the provision of an adapter for pivotally mounting a flood-lighting unit within a highway illuminating device, said adapter being arranged to support a reflector and a lamp in 30 such manner that the latter bear a constant fixed relation to each other irrespective of the adjusted position of the flood-lighting unit as a whole, the result being that the flood-lighting lamp is at all times in proper 35 focus with respect to its reflector so as to distribute the light more efficiently and effectively.

Other objects and objects relating to details of construction and economies in operation will appear more fully hereinafter.

The invention consists substantially in the combination, construction, location and relative arrangement of parts, all as will be described more fully hereinafter, as shown in the accompanying drawings illustrating a preferred form thereof, and as finally pointed out in the appended claims. In said drawings:

50 Figure 1 is a vertical sectional view of a

highway lighting unit embodying the principles of this invention;

Figure 2 is a sectional view taken on the line 2—2 of Figure 1;

Figure 3 is a sectional view taken on the 55 line 3—3 of Figure 1; and

Figure 4 is a side elevation of the complete unit shown in Figure 1.

Referring now to the drawings and more particularly to Figures 1, 2 and 3 thereof, it will be seen that the invention has been embodied in a highway lighting unit, designated generally by the reference numeral 10. This unit 10, which is mounted upon a suitable standard 11, comprises a pair of lower annular members 12 and 13 secured together by the securing elements 14. Extending upwardly from the upper edge of the annular member 13 are a plurality of arm or strap members 15 spaced equidistantly about the periphery of the member 13, the lower ends of these members 15 being preferably secured to the member 13 by means of the screws 16. Secured to the upper and free ends of the strap members 15, preferably by the screws 17, is an annular member 18, the upper edge of which constitutes a seat for the top or cover 19 of the unit. Preferably this cover 19 is hingedly secured to one side of the member 18, as at 20. (See Figure 4.)

The external appearance of the unit is of course immaterial in so far as the present invention is concerned, the particular shape being dependent entirely upon the number and form of the strap members 15. In the present instance, however, the unit 10 is of octagonal form and is provided in the sides thereof with a plurality of translucent glasses 21 secured in position in any suitable manner. The hinged cover 19 may likewise be provided with translucent glasses 22 therein or said cover may be constructed of opaque material throughout if desired.

As appears most clearly in Figures 1 and 3, the lowermost annular member 12 is provided with a centrally apertured bottom 23 across which is secured, preferably by the screws 24, a lamp socket supporting yoke 25. Rigidly mounted upon this yoke 25 in

any suitable manner is a lamp socket 26 arranged to receive a lamp 27 constituting the light source for illuminating the street or highway. It is sometimes desirable to rotate the lighting unit 10 as a body about its vertical axis and for this purpose the bottom 23 of the lowermost member 12 may be provided with a plurality of circumferentially spaced elongated slots or openings 28 through which pass the main mounting bolts 29, the arrangement being such that when these bolts 29 are loosened the unit 10 may be rotated with respect to the standard 11 within the limits of the slots 28.

Secured to and extending downwardly and inwardly from the uppermost annular member 18 are a pair of diametrically opposed supporting brackets 30, the lower ends of which are provided with threaded apertures 31. It is between these brackets 30 that the flood-lighting adapter is pivotally mounted. As appears most clearly in Figures 1 and 2, this adapter comprises a substantially U-shaped strap 32 to which is secured, preferably by welding, a second strap 33, the straps 32 and 33 being arranged substantially at right angles to one another. The free ends of the U-shaped strap 32 are each slotted, as at 34, to facilitate the mounting of the adapter upon the supporting studs 35 which are threadedly received within the apertures 31. If desired, one or more additional slots 34' may be provided for the purpose of shifting the adapter laterally into a position such as is indicated by the dotted line 34" in Fig. 1. Preferably, the slot 34' is of greater depth than that of slot 34 so that when the former slot is used the adapter may assume a lowered as well as laterally adjusted position. To remove the adapter it is only necessary to loosen the studs 35 whereupon the adapter may be lifted bodily from the supporting brackets 30.

It will be observed that the strap 33 is longitudinally curved, as at 36, substantially equidistantly to either side of its point of connection with the supporting strap 32 and that from the upper end of this curved portion 36 the strap continues in the form of an angular extension having the branches 37 and 38. Provided in the branch 37 is an opening 39 arranged to permit the passage therethrough of a winged stud 40. The lower end of the curved portion 36 of the strap 33 is reversely bent as at 41 to form a receiving channel for the lower edge of a reflector 42 which corresponds in longitudinal cross section to the curvature of the curved strap portion 36. The base of the U-shaped strap 32 is curved to correspond to the transverse curvature of the reflector 42. (See Figure 2.) The upper edge of this reflector is retained against displacement by means of a retaining clip 43, the body of which is threadedly engaged by the winged

stud 40. Preferably, the strap 33 is provided with two or more spacing pads 44 which may be spot welded to the strap and between which and the rear surface of the reflector may be disposed the felt pads 45. The reflector 42 is retained against lateral displacement by the legs of the U-shaped supporting strap 32, the arrangement being such that when the retaining clip 43 is removed or turned through an angle of substantially 90 degrees from its position shown in Figure 1, the reflector may be readily inserted into proper position with one edge thereof seated within the reversely bent end of the strap 33. The clip 43 may then be positioned as shown with one end thereof overlying the opposite edge of the reflector and the winged stud 40 tightened to secure said edge against displacement.

Rigidly secured to the branch 38 of the strap 33 is a lamp socket 46 for reception of a second lamp 47, this latter lamp being the source of light for flood-lighting purposes. By reason of the fact that the socket 46 and the reflector 42 are both mounted upon a common support, the focus of the flood-lighting lamp 47 bears a constant and fixed relation to the reflector 42. Once the proper focal relation be determined it need never, and in the present instance cannot be disturbed irrespective of the position to which the flood-lighting unit as a whole may be shifted.

It will be apparent from the foregoing that this invention provides a flood-lighting arrangement capable of ready and simple mounting in a highway lighting unit wherein the focal relation between the flood-lighting source and its reflector is at all times fixed at the same time that the flood-lighting unit as a body is capable of a wide range of movement for the purpose of directing the rays of light at practically any angle with respect to the horizontal. Furthermore, it will be apparent that any suitable means (not shown) may be employed, if desired, for effecting adjustment of the lamp socket 46 along its longitudinal axis in order to obtain a desired focal relation between lamp and reflector. Once this adjustment is made, however, the focal relation is fixed and remains so irrespective of the adjusted position which the unit, as a body, may assume. At the same time, it will be seen that the flood-lighting unit is capable of being readily removed from its main supports without disrupting its organization or disturbing the focal adjustment between the light source and its reflector.

It will, of course, be understood that various changes may be made from time to time in the general arrangement of this invention without departing from the spirit or principles thereof, and it is accordingly intended to claim the same broadly as well as specifically as indicated in the appended claims.

What is claimed as new and useful is:

1. In a lighting unit provided in its upper

- portion with an annular band, an adapter for facilitating the mounting of a flood-lighting unit therein comprising a pair of fixed lateral supports respectively secured in downwardly extending relation to diametrically opposed sides of said band, means pivotally carried upon said supports for supporting a reflector, and a lamp receiving socket also secured upon said reflector supporting means and arranged with respect thereto such that when a lamp is inserted in said socket it bears a constant fixed relation with respect to said reflector irrespective of any adjusted position of said adapter. 5 70
2. In a lighting unit provided in its upper portion with an annular band, an adapter for facilitating the mounting of a flood-lighting unit therein comprising a pair of fixed supporting arms respectively secured in downwardly extending relation to diametrically opposed sides of said band, a substantially U-shaped member extending between said supporting arms, means for respectively securing the sides of said member to said supporting arms, a strap member extending transversely with respect to and secured to the base of said U-shaped member, said members serving conjointly as a support for a reflector, means for removably securing a 20 75 reflector in position upon said members, and an electric light bulb carried by said strap member in proper focal relation with respect to said reflector. 25 80
3. In a lighting unit provided in its upper portion with an annular band, an adapter for facilitating the mounting of a flood-lighting unit therein comprising a pair of relatively fixed supports respectively secured to and depending from opposed sides of said band, a transversely extending strap member supported by said supports, a second strap member secured to and extending beyond either side of the plane of said transverse strap member, and a concave reflector supported by said strap members, said latter members being respectively curved to correspond to the transverse and longitudinal curvatures of said reflector. 40 85
4. In a lighting unit, an adapter for facilitating the mounting of a flood-lighting lamp therein comprising a pair of interconnected strap members respectively curved to correspond to the transverse and longitudinal curvatures of a concave reflector, a concave reflector arranged to be removably carried by said members, means on one of said members for commonly supporting both of said members for rotation about a relatively fixed axis, said means being further operative to preclude lateral displacement of said reflector, and means on the other of said members for supporting an electric light bulb independently of said reflector and in fixed focus with respect thereto. 45 90
5. A flood-lighting unit comprising a pair 50 95 of inter-connected strap members arranged crosswise with respect to each other, a concave reflector arranged to be removably supported upon said members, the latter being respectively curved to correspond to the transverse and longitudinal curvatures of said reflector, means on one of said members constituting a rigid support for a lamp socket arranged with the axis thereof lying in a plane disposed exteriorly of and paralleling the edge plane of said reflector, and means for commonly supporting said members in angularly adjusted position about an axis extending at right angles to that of said lamp socket. 55 100
6. A flood-lighting unit comprising a strap member having a curved portion corresponding to the curvature of a concave reflector, a concave reflector arranged to be seated in said curved portion, means operatively associated with said strap for removably securing said reflector in position, an integral extension on said strap projecting forwardly of and in a direction substantially normal to the plane of the edge of said reflector, and a lamp receiving socket secured to said extension whereby to hold a lamp in spaced, out-of-contact relation with respect to said reflector. 60 105
7. A flood-lighting unit comprising a strap member having a curved portion corresponding to the curvature of a concave reflector, a concave reflector arranged to be seated in said curved portion, means operatively associated with said strap for removably securing said reflector in position, an integral extension on said strap projecting forwardly of and beyond the plane of the edge of said reflector, a lamp receiving socket secured to said extension whereby to hold a lamp in spaced, out-of-contact relation with respect to said reflector, and means for supporting said strap upon a relatively fixed support, said means serving further to retain the reflector against lateral displacement. 65 110
8. A flood-lighting unit comprising a strap member having a curved portion, one end of said curved portion being reversely bent to form a channel and the other end thereof being provided with an angular extension, a concave reflector arranged to be supported by said curved portion with one edge thereof seated in said channel, means operatively associated with one branch of said extension for removably engaging the opposite edge of said reflector, and a lamp receiving socket secured to the other branch of said extension for supporting a lamp in fixed, out-of-contact relation with respect to said reflector. 70 115
9. A flood-lighting unit comprising a strap member having a curved portion and an angular extension, a concave reflector arranged to be received in said curved portion, one branch of said extension lying substantially in the plane of the reflector edge and 75 120
10. A flood-lighting unit comprising a strap member having a curved portion and an angular extension, a concave reflector arranged to be received in said curved portion, one branch of said extension lying substantially in the plane of the reflector edge and 80 125
11. A flood-lighting unit comprising a strap member having a curved portion and an angular extension, a concave reflector arranged to be received in said curved portion, one branch of said extension lying substantially in the plane of the reflector edge and 85 130

the other branch thereof projecting in a direction normal to said plane, and a lamp socket secured to said projecting branch with the lamp-receiving end thereof presenting toward but terminating short and in advance of the adjacent edge of said reflector.

10. A flood-lighting unit provided in its upper portion with an annular band and comprising a concave reflector, a pair of interconnected strap members arranged crosswise with respect to each other to constitute a support for said reflector, a pair of relatively fixed supports respectively secured to and depending from opposite sides of said band slotted lateral extensions at opposite ends of one of said strap members, bolts passing through the slots in said extensions and into threaded engagement with said fixed supports for securing the unit in fixed position, said slots being arranged with their open ends presenting downwardly whereby to permit said unit to be bodily removed from said supports when said bolts are merely loosened.

25. 11. A flood-lighting unit provided in its upper portion with an annular band and comprising a concave reflector, a pair of interconnected strap members arranged crosswise with respect to each other to constitute a support for said reflector, a pair of relatively fixed supports arranged to either side of said reflector and depending from said annular band, lateral extensions at opposite ends of one of said strap members for engagement with said fixed supports, and means in said lateral extensions for permitting said unit to be bodily shifted along the plane common to said extensions.

40. 12. A flood lighting unit comprising a reflector, said reflector being arranged for rotation about an axis extending transversely across the body thereof, and means for effecting lateral adjustment of said reflector bodily with respect to said axis whereby to vary the radial distance between said axis and the arc of rotation of the reflector.

50. 13. In a lighting unit provided in its upper portion with a supporting structure for a flood-lighting unit, said structure including a depending arm, in combination, an adapter for facilitating the mounting of said flood-lighting unit in position comprising a pair of interconnected strap members arranged cross-wise with respect to each other, means on one of said strap members for commonly supporting both of said members from the lower end of said depending arm whereby to permit the rotation of said strap members as a unitary assembly about a relatively fixed 60 transversely extending axis, a concave reflector arranged to be removably carried by said members, and cooperating elements associated with each of said strap members for precluding lateral displacement of said reflector.

14. In a lighting unit provided in its upper portion with a supporting structure for a flood-lighting unit, said structure including a depending arm, in combination, a transversely extending strap member adapted to be rotatably supported upon said arm, a second strap member extending transversely with respect to and secured to said first-mentioned strap member, said strap members serving conjointly as a support for a reflector, means for removably securing a reflector in position upon said members, and an electric lamp adapted to be carried by one of said strap members in fixed focal relation with respect to said reflector.

15. In a lighting unit provided in its upper portion with a supporting structure for a flood-lighting unit, said structure including a depending arm, in combination, means pivotally carried upon said arm for supporting a reflector, and a lamp-receiving socket also secured upon said reflector supporting means and arranged with respect thereto such that when a lamp is inserted in said socket it bears a constant fixed relation with respect to said reflector irrespective of any adjusted position of said reflector supporting means.

16. A flood-lighting unit comprising a concave reflector, an arcuately shaped member constituting a supporting saddle for said reflector, a relatively fixed support about which said reflector and its supporting saddle are commonly rotatable, a lateral extension on said reflector supporting saddle and intersecting a plane spaced forwardly from and paralleling that of the reflector edge, and a lamp receiving socket secured to said extension with the longitudinal axis thereof lying in said plane.

17. A flood-lighting unit comprising a member having a curved portion corresponding to the curvature of a concave reflector, a concave reflector arranged to be seated in said curved portion, means operatively associated with said member for removably securing the reflector in position, an integral extension on said member projecting forwardly of and in a direction intersecting the plane of the edge of said reflector, and a lamp receiving socket secured to said extension whereby to hold a lamp in spaced, out-of-contact relation with respect to said reflector.

In testimony whereof, I have hereunto affixed my signature.

HARRY YALE MAGEOCH.
